Fig.5

To all whom it may concern:

Be it known that I, Sidney Arthur Cook, a subject of the Queen of Great Britain and Northern Ireland, residing at 391 Stratford Road, Shirley, Birmingham, England, have invented a new, original, and ornamental Design for a Signaling Lamp, of which the following is a specification, reference being had to the accompanying drawing, forming a part thereof.

Fig. 1 is a side elevational view of a signaling lamp showing my new design;

Fig. 2 is a top plan view thereof;

Fig. 3 is a front elevational view;

Fig. 4 is a rear elevational view; and

Fig. 5 is a bottom plan view.

I claim:

The ornamental design for a signaling lamp, as shown.
